FIG. 4.

G. H. Benjamin
INVENTOR.

UNITED STATES PATENT OFFICE.

GEORGE HILLARD BENJAMIN, OF NEW YORK, N. Y.

TUNNEL-KILN.

1,292,568.

Specification of Letters Patent. Patented Jan. 28, 1919.

Application filed January 8, 1918. Serial No. 210,897.

To all whom it may concern:

Be it known that I, GEORGE HILLARD BENJAMIN, a citizen of the United States, residing at New York, in the county and State of New York, have invented certain new and useful Improvements in Tunnel-Kilns, of which the following is a specification.

In a companion application, Serial No. 169,865 filed May 21, 1917, I have described an improvement in tunnel kilns, in which the heat effects are due to heat radiated from a series of combustion chambers (in which gas and air are burned) located within the body of the kiln, and the air heated 15 to a high temperature by means of hot blast stoves arranged exterior to the kiln.

My present invention consists in a modified construction, wherein in place of the combustion chambers located within the kiln, a single combustion chamber is located exterior to the inner wall of the kiln and heated by gas and air, and the heat from said inner wall radiated into the body of the kiln, and air heated by hot blast stoves, 25 as in my former application above referred to, introduced into the body of the kiln.

The particular advantage of the construction shown in my present application, over that shown in my former application, is found in the fact that my improved construction permits of more rapid and effective revolution of the heat units by combustion of the gas and air, than is the case with the construction of my former application, as well 35 as other advantages, which will be referred to in the specification.

The accompanying drawings will serve to illustrate my invention, in which:

Figure 1 is a transverse section taken substantially on the line I—I of Fig. 3.

Fig. 2 is a longitudinal vertical section taken substantially on the line II—II of Fig. 3.

Fig. 3 is a horizontal section taken substantially on the line III—III of Fig. 2.

Fig. 4 is a vertical section taken substantially on the line IV—IV of Fig. 3.

In the drawings, 5 indicates the body of the kiln, which is composed of the outer wall 6 and the inner wall 7. A combustion chamber 8 is provided between the walls 6 and 7, such chamber being sufficiently large to permit free radiation of flame from the gas and air burners 9. Situated in the bottom of the chamber 8, are masses of brick 10, loosely piled, so as to provide air spaces

11 between the brick. In the drawings this mass of brick 10 is shown as arranged at an angle to the wall 7 and in front of the orifice 12 of the gas and air burners 9. 60

In the operation of the kiln, a stream of gas and air, ignited, is driven on the mass of brick. Under normal conditions the combustion of the gas and air at the burner orifice is instantaneous, and all the heat units 65 are liberated at once, at which time the heated mass of brick 10 has no particular effect. If, however, the proper proportions of gas and air introduced at the burner 9, do not exist, as for instance, there being more 70 gas than is required, instantaneous combustion does not take place at the burner orifice, but only partial combustion, the stream carrying the excess of carbon on to the brick work 10, where it is disassociated, to be almost immediately burned in the upper portion 75 of the chamber 8. In order to obtain instantaneous combustion, it is necessary that the chamber 8 shall be sufficiently large to permit free evolution of the flame due to the 80 combustion of the elements contained in the introduced gas and air. I make the above explanation, as it is not possible to show, in the drawings, the parts, by size, which will indicate the results which are to be obtained. 85

The gas and air burners 9 are situated at equal distances apart along the chamber 8 on the outside of the furnace, as indicated in Fig. 3, and are fed from gas and air pipes 13—14 through branch pipes 15—16 controlled by valves 17—18. It will be understood that by reason of the arrangement of the burners, the temperature of the treating chamber 19 can be regulated as desired along its length. 95

Connected to the upper portion of the combustion chamber 8, is a flue 20 which communicates with the cross flues 21 which in turn communicate with down flues 22 connected to one or the other of the pairs of 100 hot blast stoves 23—23^a or 24—24^a (as shown in Fig. 3), which stoves are in turn connected to chimney flue 25, the hot products of combustion serving to heat the pair of hot blast stoves at the time in circuit, in passing 105 through them, on the way to the chimney flues 25. Two hot blast stoves 23—23^a and 24—24^a are arranged on each side of the kiln. Each of these stoves consists of a combustion chamber 26 and a heating chamber 27. The down flues 22 are shown as connected through a flue 28 to the bottom of the 110

combustion chamber 26, and the bottom of the heating chamber 27 through flue 29, is connected at one side, to the chimney flue 25, and at the other side to flues 30 arranged 5 longitudinally on both sides of the bottom of the kiln, and having openings 31 communicating with the interior of the treating chamber 19 of the kiln.

Situated in the flues 29 are butterfly valves 10 32. When the valves are in the position shown in Fig. 3, the products of combustion from the combustion chamber 8 pass through the hot blast stoves 23—24 to the chimney flue 25, heating the heating chamber 27 by 15 their passage. Additional means may be provided for heating the heating chamber 27, consisting of a gas and air burner 33, as indicated in dotted lines in connection with hot blast stoves 24—24^a of Fig. 3. Connected also to the lower part of the combustion chamber 26, is a flue 34 communicating with the external air, or with a source 20 of heated air.

Situated between the down flues 22 and 25 the air flue 34, is a damper 35. When the damper is in the position shown at the left of Fig. 3, the air flue 34 is closed; when the damper 35 is in the position shown at the right of Fig. 3, the passage for the products 30 of combustion from the down flues 22 is closed and the passage through the air flue 34 is open. When the air flue 34 is open, air passes into the combustion chamber 26, thence through the heating chamber 27, and 35 with the butterfly valve 32 in the position shown in the figure, through the flue 29 to longitudinal flue 30, thence through openings 31 to be emitted into the chamber 19 in the interior of the kiln.

40 From the above it will be seen that when the hot blast stoves 23—24 are being heated by the products of combustion, the hot blast stoves 23—24^a are simultaneously heating air introduced through the air flues 34, and 45 are discharging the air so heated into the treating chamber 19. When the butterfly valves 32 are reversed, the operation of the pairs of hot blast stoves is correspondingly reversed.

50 Forming a part of the chamber 19, but situated below the bottom of the kiln, is a chamber 19^a, connected by means of a series of flues 36 to a longitudinal flue 37, closed at one end, but connected at the other end to 55 the inlet orifice of a pump 38. The outlet orifice of the pump discharges into the atmosphere, or if desired, into a recuperator to heat the air introduced into the hot blast stoves through the air flue 34. This arrangement is obvious, and hence is not shown in the drawings.

Mounted on a trackway 39 in chamber 19^a, are a series of trucks 40, on which are located the materials 41 to be treated. The 60 top of each truck has formed in it an open-

ing 42, and the sides of the trucks are bent downward as shown at 43 and move through a body of sand 44 in troughs 45 carried by the walls of the chamber 19^a, this construction forming a practical air seal.

The operation of the kiln will be readily understood. The heat due to the combustion of gas and air and set free in the combustion chamber 8, heats the wall 7, the heat being transmitted to the interior of the 75 treating chamber 19. At the same time, the air heated by the pair of hot blast stoves, then in operation, is transmitted into the interior of the treating chamber 19 and passes to the top of the chamber along the wall 7, 80 gathering heat, and then moves downward under the action of the pump 38 through the material 41 that is to be treated, through openings 42 to flues 36 to inlet of pump and then to outlet of pump. As above indicated, 85 in order to conserve heat, the air introduced into the chamber 19 may be circulated through a recuperator if desired.

It will be seen from the above description, that the heating effects are due, first, to the 90 radiated heat from the wall 7, and second, to the heat conveyed by the air introduced into the chamber 19, and that by reason of the construction, the gases of combustion do not come in contact with the material 95 under treatment, the chamber 19 acting as a muffle, so far as relates to the combustion taking place in the combustion chamber 8, and that the air introduced into the chamber 19, while serving as a medium for heating the material, also serves to absorb the moisture set free from the material under treatment, and to convey such moisture out of the treating chamber 19. By regulating the temperature along the treating chamber 100 19, as also by regulating the body of air introduced into the chamber, various technical effects can be obtained. Thus, for instance, the chamber can be given a comparatively low temperature at the entrance end 110 and a large body of air transmitted; the temperature can be increased at the center of the kiln and the transmitted air decreased; the temperature can be quite cut off at the exit end, while the body of air transmitted can be materially increased, and this air, by manipulating the hot blast stoves, 115 can be cooler in temperature than the air admitted through the hot blast stoves at other portions of the length of the kiln.

I have not entered into detailed descriptions of the manipulations of valves, etc., necessary to obtain the variations of temperatures, etc., along the length of the kiln, as it is believed that it will be obvious to 125 those skilled in the art to which this invention belongs.

Having thus described my invention, what I claim is:

1. In a tunnel kiln, the combination of a 130

treating chamber, a combustion chamber arranged external to the treating chamber and adapted to heat the treating chamber by radiation, means for introducing gas and air under pressure into the combustion chamber, means situated in the combustion chamber adapted to accelerate the combustion of the combustible bodies introduced into the combustion chamber, and means for conveying the products of combustion away from the combustion chamber.

2. In a tunnel kiln, the combination of a treating chamber, a combustion chamber arranged external to the treating chamber and adapted to heat the treating chamber by radiation, means for introducing gas and air into the combustion chamber, means for conveying the products of combustion away from the combustion chamber, and means for causing heated air to pass through the treating chamber.

3. In a tunnel kiln, the combination of a treating chamber, a combustion chamber arranged external to the treating chamber, gas and air burners projecting into the combustion chamber at opposite sides of the treating chamber, refractory heat radiating bodies situated in the combustion chamber in front of the gas and air burners, and an exit flue for the products of combustion from the combustion chamber.

4. In a tunnel kiln, the combination of a treating chamber, a combustion chamber arranged external to the treating chamber, means for introducing gas and air into the combustion chamber, means for conveying the products of combustion away from the combustion chamber, air heating stoves arranged in pairs on each side of the kiln, means for causing the products of combustion at one time to pass through one pair of stoves and to the chimney stack, and for causing air at the same time to pass through the other pair of stoves to the interior of the kiln, together with means for causing air delivered to the treating chamber to pass through and out of the treating chamber.

5. In a tunnel kiln, the combination of a treating chamber, pairs of hot blast stoves arranged on each side of the exterior of the treating chamber, means for heating one pair of stoves at one time, and means for introducing at the same time air into the other pair of previously heated hot blast stoves and causing said air to be delivered into, passed through and drawn from the treating chamber.

6. In a tunnel kiln, the combination of a

treating chamber, a combustion chamber arranged to include the side walls and top of the treating chamber and sufficient in dimensions to permit the free development of heat from the gaseous fuel introduced into the combustion chamber, means for introducing combustible gaseous fuel into the combustion chamber at the lower part thereof and at both sides of the combustion chamber, means in the combustion chamber for accelerating the combustion of the introduced gaseous fuel, and an exit flue for the products of combustion connected to the top of the combustion chamber.

7. In a tunnel kiln, the combination of a treating chamber, a combustion chamber, gas and air burners arranged on each side of the external walls of the combustion chamber, a mass of loosely piled heat radiating material situated in the bottom of the combustion chamber and near the side walls separating the combustion chamber from the treating chamber, and an exit flue for the products of combustion connected to the combustion chamber.

8. In a tunnel kiln, the combination of a treating chamber, a combustion chamber arranged external to the treating chamber, said combustion chamber of greater lateral diameter at its lower portions, on each side of the treating chamber, than at its upper portions or that part over the roof of the treating chamber, gas and air burners projecting into the combustion chamber, at such portion having the greatest lateral diameter, masses of heat radiating material situated in said combustion chamber in the parts having the greatest lateral diameter, and an exit flue for the products of combustion connected to the combustion chamber.

9. In a tunnel kiln of the class described, the combination of a treating chamber, a heating element, hot blast stoves arranged on each side of the treating chamber in pairs, means for alternately heating the hot blast stoves in pairs by outgoing products of combustion from the heating element, and means connected to the hot blast stoves for supplementing the heat imparted by the products of combustion to the hot blast stoves.

In testimony whereof, I affix my signature, in the presence of two witnesses.

GEORGE HILLARD BENJAMIN.
